HOLDING MEANS FOR VANITY CASES

Filed Dec. 14, 1928

UNITED STATES PATENT OFFICE

WILLIAM G. KENDALL, OF NEWARK, NEW JERSEY

HOLDING MEANS FOR VANITY CASES

Application filed December 14, 1928. Serial No. 326,102.

This invention relates to vanity cases, and has for an object to provide an improved construction for holding a compact plate removably in position, the construction being such that the compact plate may hold any kind of powder, rouge and the like and renewals may be made at any time without the use of tools.

Another object of the invention is to provide in a vanity case, a compact holding device which is swingably mounted in the case and which resiliently holds a compact plate in position.

A further object, more specifically, is to provide a holding structure for removable plates, the holding structure being swingably connected to the casing or to an ornamental filling ring fitting into the casing.

In the accompanying drawings,—

Figure 1 is a plan view of the vanity case disclosing an embodiment of the invention, the vanity case being shown in an open position;

Figure 2 is a rear view of the central part of the vanity case shown in Figure 1, certain parts being broken away for illustrating how one of the plate carrying rings is mounted;

Figure 3 is a longitudinal sectional view through Figure 1 on the line 3—3, the same being on an enlarged scale;

Figure 4 is an enlarged fragmentary sectional view through Figure 1 on the line 4—4;

Figure 5 is a sectional view through one of the compact plate holders;

Figure 6 is a sectional view through a second form of compact plate holder;

Figure 7 is a plan view of the compact plate holder shown in Figure 6, certain parts being broken away for illustrating the abutment or upstanding wall.

Referring to the accompanying drawings by numerals, 1 and 2 indicate the casing of the vanity case, the part 1 acting as a lid and the part 2 acting as a body. Pivotedly connected to the body 2 is a mirror 3 which may be folded over into body 2 so that lid 1 when closed will enclose the mirror 3, as well as the articles carried in the lid 1 and body 2.

Arranged in the lid 1 is a compact ring 4 pro-

vided with an upstanding wall 5 merging into a back or holding ring 6. The wall 5 is formed of approximately a half-circle and is spaced from the edge 7 of the opening in ring 4. It will thus be seen that the holding ring 4 is formed substantially as a channel iron for the half adjacent the hinge 8. For the other half two ring sections are provided, one being part of the ring 6. The loose or free part 9 of ring 6 is more or less resilient and acts to clamp the compact plate against accidental removal. Ring 4 is provided with a thumb extension 10, whereby the ring may be swung substantially out of the lid 1 so that the fingers may grasp the front and rear of the compact plate when it is desired to pull the same away from the wall 5, whereby the plate will be ejected. A new filled plate may be substituted and ring 4 moved back to the position shown in Figures 1 and 3. The ring 4 is also provided with an extension 11 having a looped portion 12 forming one of the knuckles of hinge 8, whereby the pintle of hinge 8 will swingably support the ring 4 and thus substantially permanently connect the ring with the lid 1, while permitting the ring to be swung inwardly and outwardly, as desired.

In the body 2 the same inventive idea is presented but worked out in a manner to permit a rouge cake 13 and its holding plate to be removably held in place within the body. This structure is provided in the bottom of the ring 14, whereby the mirror 3 may be readily nested within the body 2 when the vanity is closed. The detail structure of the rouge plate holding ring 15 is identical with the detail structure of the ring shown in Figures 3 and 5 and will therefore need no additional description and the same reference numerals will be used. There is, however, an added thumb member 16 for permitting the ring 15 to be swung back and forth through the opening 17 in ring 14. Also, the extension 11' is formed with a knuckle 12' the same as ring 4, but the extension 11' is positioned to extend through the opening 18 in ring 14. A pintle 19 extends through the knuckle 12' and through suitable bearing or supporting fittings 20 and 21 soldered or

otherwise permanently secured to the rear surface of ring 14. From Figure 4 it will be noted that ring 14 is substantially channel-shaped and the inner wall 22 is arc-shaped in cross-section to form a recess for receiving both the ring 15 and the mirror 3. It will thus be seen that the ring 15 is pivotally mounted on the filling ring 14, while the ring 4 is pivoted to swing around the pindle of hinge 8. The wall 22 is provided with one or more pressed portions 23 presenting nibs acting to resiliently lock ring 15 in its normal position, as shown in Figure 3. When the ring 15 is moved inwardly or outwardly it must snap past this projection, which may be done as the wall is sufficiently resilient to allow this action.

What I claim is:—

1. A vanity case, comprising a body, a lid hinged to the body at one point, a mirror hinged to said body at the diametrically opposite point, said mirror being adapted to be swung into said body while the lid is adapted to close the body, a compact plate holder means for swingably connecting said holder to said lid, a rouge plate holder and means for swingably connecting said rouge plate holder to said body said compact plate holder being positioned to swing into and out of said lid and said rouge plate holder being positioned to swing into and out of said body.

2. In a vanity case, a powder cake plate holder, comprising a removable ring, an arc-shaped wall secured to the rear face of the ring, and a clamping ring secured to one edge of said wall, said clamping ring being resilient and acting to hold the plate against said wall and the first-mentioned ring.

3. In a vanity case, a powder plate holder, including a ring formed with an extension provided with a hinged knuckle, means coacting with the knuckle for pivotally mounting said extension and ring, a wall connected with said ring on one face, said wall forming part of a circle, and a clamping ring formed integral with the outer edge of said wall, said clamping ring extending beyond said wall to provide a clamping section for said plate.

4. In a vanity case, means for holding a powder carrying plate in the vanity case, said means including a filling ring formed channel-shaped in cross section, one part of the filling ring having an opening, a plate carrying ring having hinge means extending through said opening, whereby the ring is pivotally mounted, and a clamping ring connected with the plate carrying ring for removably clamping a plate to the plate carrying ring, whereby the parts may be swung outwardly and the plate applied and removed at will.

5. In a vanity case, a powder carrying plate holding member, said holding member including a ring provided with an extension having a hinged knuckle, an arc-shaped wall

and a clamping ring connected with said wall at the opposite edge to the first-mentioned ring, said clamping ring being of substantially the same size as the first-mentioned ring.

6. In a vanity case, a swingable ring adapted to receive and hold a powder-carrying plate, said ring having an apertured body and an up-standing wall against which the edge of said plate is adapted to rest, said wall extending from one edge of said body, a projection extending from said body acting as a pivotal support, and a retaining and clamping ring connected to the outer part of said wall and positioned substantially parallel to said body for the clamping of said plate.

WILLIAM G. KENDALL.
